UNITED STATES PATENT OFFICE.

RICHARD D. GALLAGHER, JR., OF NEW YORK, N. Y., ASSIGNOR TO STANDARD COUPLER COMPANY, OF NEW YORK, N. Y., A CORPORATION OF NEW JERSEY.

DRAFT-SPRING YOKE CONNECTION FOR DRAW-BARS.

SPECIFICATION forming part of Letters Patent No. 713,627, dated November 18, 1902.

Application filed August 26, 1901. Serial No. 73,286. (No model.)

To all whom it may concern:

Be it known that I, RICHARD D. GALLAGHER, Jr., a citizen of the United States, residing at New York, in the county of New 5 York and State of New York, have invented certain new and useful Improvements in Draft-Spring Yoke Connections for Draw-Bars; and I do hereby declare the following to be a full, clear, and exact description of 10 the same, reference being had to the accompanying drawings, forming a part of this specification, and to the letters of reference marked thereon.

This invention has for its object to provide 15 a connection between the draft-spring yoke or strap and the draw-bar of a car-coupler which will permit of the utilization of draw-bars of ordinary construction and provide for a pivotal action of the draft-spring yoke or 20 strap, whereby the draw-bar may swing laterally with respect to said yoke or strap in order to avoid breakage at the point of connection.

The invention consists in certain novel 25 details of construction and combinations and arrangements of parts, all as will be now described, and pointed out particularly in the appended claims.

Referring to the accompanying drawings, 30 Figure 1 is a vertical section through the rear end of a draw-bar constructed on the lines of the Master Car-Builders' standard, with a draft-spring yoke or strap connected therewith in accordance with my present improvements. Fig. 2 is a top plan view of the same 35 with the underlying plate or cap shown in dotted lines. Fig. 3 is a transverse section of one of the plates or caps which is interposed between the side of the draw-bar and the end 40 of the yoke or strap.

Like letters of reference in the several figures indicate the same parts.

The letter A indicates the rear end of a draw-bar, which draw-bar is in the illustrations shown as being built or formed on the 45 lines of the Master Car-Builders' standard, and therefore has the usual projections A', over which the yoke or strap normally hooks, being held in place by two or more bolts or 50 rivets. In accordance with my present in-

vention and in order to provide for a pivotal connection between the draw-bar and yoke without sacrificing the strength of the connection I provide cap-plates B, which fit over the projections A', said cap-plates being held 55 in position by bolts or rivets C, passing through one of the holes provided in the end of the draw-bar and having their heads brought down flush with the surface of the cap-plates. The axis of the pivotal connection 60 is coincident with the other hole in the draw-bar, and it will be understood that either hole may be so utilized. Consequently the forward ends of the cap-plates B are formed on a radius with said axis as a center. The yoke 65 or strap D has its ends D' bent inwardly, and the bearing-surfaces of the hooks so formed are curved to fit the forward ends or bearing-surfaces of the caps B, as well illustrated in 70 Figs. 1 and 2. A through-bolt passes through the hole which forms the axis of the joint to secure the ends of the strap to the draw-bar. Thimbles are provided which surround the 75 ends of said bolt and are formed integral with or seated in the cap-plates themselves, whereby a more extended bearing-surface is afforded and additional strength secured. As illustrated in Fig. 1, these thimbles or ferrules are indicated by the letter F and are made separate from the cap-plates B, but seat in recesses 80 formed therein, and the pivot-bolt G passes through the draw-bar, cap-plate, and ferrules, serving to retain the yoke or strap firmly in position, but at the same time permitting it 85 to oscillate or pivot transversely, as before explained.

In accordance with the present invention, the ordinary draw-bars now in common use may be conveniently and readily converted into a more highly approved form and the 90 adaptability of the draw-bar correspondingly increased. The expense of such conversion is comparatively slight and does not call for any modification of the draw-bar itself, and, in fact, in practice it will be found convenient 95 to continue the construction of such draw-bars on the lines now laid down in order that they may be used for either the rigid or pivotal form of connection, as desired. Where a pivotal connection is desired it is only nec- 100

essary to furnish cap-plates and the improved form of yoke, although even the latter element may in some instances be dispensed with and the ordinary yoke employed, although it is desirable that the curved bearing-surfaces should be provided in order to prevent excessive wear and to provide an extended surface for taking up the strains incident to the use of draft-gear.

10 Having thus described my invention, what I claim as new, and desire to secure by Letters Patent, is—

15 1. The combination with the draw-bar having the projections at top and bottom, the cap-plates united thereto by a through-bolt and having another bolt-opening passing therethrough, the forward ends of said cap-plates being formed on a radius with said last-mentioned bolt-hole as a center, of a yoke embracing said cap-plates and having its forward ends fitted to said curved surfaces, a through-bolt passing through said last-mentioned aperture and the yoke to form a piv-

20 otal connection, and thimbles or ferrules projecting outwardly from the cap-plates and surrounding the bolt; substantially as described. 25

2. The combination with a draw-bar having projections at top and bottom at the rear end, cap-plates surrounding said projections and secured in place by a through-bolt having its ends or heads made flush with the outer faces of the cap-plates, the forward ends of said cap-plates being formed on a radius with a second bolt-hole as a center and a bolt passing through said last-mentioned hole, of thimbles independent of said cap-plates held in position by said bolt, and a yoke having its forward ends hooked and curved to engage the forward ends of the cap-plates, said yoke being retained in position by the cap-plates, 30 thimbles and through-bolts; substantially as described. 35
